UNITED STATES PATENT OFFICE.

TOM MOORE, OF HAYS, KANSAS.

POST-HOLE DIGGER.

1,235,588.

Specification of Letters Patent.

Patented Aug. 7, 1917.

Application filed February 7, 1917. Serial No. 147,165.

To all whom it may concern:

Be it known that I, TOM MOORE, a citizen of the United States, residing at Hays, in the county of Ellis, State of Kansas, have 5 invented certain new and useful Improvements in Post-Hole Diggers; and I do hereby declare the following to be a full, clear, and exact description of the invention, such as will enable others skilled in the art 10 to which it appertains to make and use the same.

This invention relates to post hole diggers.

The object of the invention is to provide a post hole digger which may be mounted 15 upon trucks or wagon bodies and operated therefrom to dig or bore holes which will always be vertical, regardless of the position which the wagon, truck or other support may assume as a result of the uneven 20 or inclined contour of the ground surface. To this end, the invention comprises a support having a swiveled bearing within which the digger earth boring device is operative to be entered into the earth or withdrawn 25 therefrom.

A further object of the invention is to provide a suitable connection between the boring element or bit and the stem, whereby the bit will be free to be lifted without rotation when it is desired to withdraw the 30 apparatus from the hole.

With the above objects in view and such others as may hereinafter appear, my invention will now be fully set forth and 35 described, reference being had to the accompanying drawings.

In the drawings:—

Figure 1 is an elevation of the device mounted upon a vehicle body,

40 Fig. 2 is a vertical section,

Fig. 3 is a plan view of the mounting with the boring stem removed,

Fig. 4 is a plan view of the bit, and

45 Fig. 5 is a section on line 5—5 of the bit structure.

Referring more particularly to the drawings, 1 indicates a plank or other suitable support which may be projected from the rear or side of a vehicle body so as to support the digger or boring implement freely over the spot which is to be entered by the bit. The plank 1 carries a pair of eye bolts 2, the eyes thereof projecting vertically 50 above the plank with their eyes in longitudinal alignment and providing a socket for

the shanks 3 of the yoke sections 4, the shanks 3 being semi-circular in cross section so that when placed together they provide a cylindrical stem which fits within the socket provided by the eye bolts. Also when 60 the yoke sections 4 are placed together, they provide a gimbal between whose arms a block 5 may be swiveled, trunnions 6 upon opposite sides of the block 5 entering within bearings in the free ends of the arms of the 65 elements 4. The block 5 is vertically apertured, and threaded to receive a threaded stem 7 whose rotation in the block 4 raises and lowers the stem and consequently the bit 8 which is removably secured within the 70 lower end of the stem in a manner which will hereinafter appear. At suitable intervals, the stem is provided with recesses or apertures 9 within which the bolt 10 which is threaded into a collar 11 of a cross bar 75 or handle member 12 may enter, the spaced relation of the opening 9 along the stem permitting the adjustment of the handle bar 12 to an appropriate or convenient level for 80 the operator.

The lower end of the bit stem 8' is transversely apertured to receive a pin 13, and above the pin 13 is provided a second aperture within which the pin 14 may be removably projected. The pins 13 and 14 coöperate 85 with suitable sockets or recesses in the bit 8 to provide a swivel and ratchet mechanism whereby the bit may be driven into the ground by rotation, but may be withdrawn without rotation. Thus, the pin 13 operates 90 in a cylindrical opening 15 formed at the lower end of the vertical socket 16 within which the stem 8' projects, the cylindrical recess 15 being of sufficient diameter to permit the pin 13 to rotate with 95 the stem relative to the bit in either direction. The pin 14, on the other hand, co-operates or fits within a transverse socket or recess 17 in the upper end of the bit, so that when the pin 14 rests within the recess 17, the stem and bit are locked together for simultaneous rotation. However, the cylindrical recess 15 is of sufficient vertical length to permit such a relative play of the stem 8' 100 within the bit as to free the pin 14 from its locked engagement with the bit when the stem is elevated. Thus, the action of the mechanism is as follows: When the stem is rotated so as to turn downwardly in the block 5, the pin 14 enters into the recess 17 105 110

so as to lock the bit to the stem, continued rotation of the stem then causing the bit to enter into the ground and bore a hole. However, when the stem 7 is rotated in the reverse direction, so as to be lifted from the ground, the pin 14 passes out of the recess 17, and the pin 13 bears against the upper end of the recess 15, but since the pin 13 may rotate within the recess 15, the bit will be lifted from the ground without rotation. In this manner, the hole may be properly freed from the earth which has been loosened on the down trip.

The operation of my improved device has been pointed out in the course of the foregoing description, but it should be noted in addition to its simple operation, that it may be readily dismounted from the support 1 and stored within wagon or other vehicle bodies, and that when dismounted its several parts are disassembled for close packing or storing. Furthermore, the parts are simple in construction and of such character and design that there is little mechanism to be destroyed or injured, and if broken may be economically replaced.

What I claim as my invention is:—

1. A post hole digger comprising in combination, a support, having alined socket elements, a gimbal comprising separable

half sections and having shanks fitted in said socket elements, a block pivotally mounted between the arms of the gimbal, a threaded stem operative vertically in the block, adjustable handle bars on the stem, and a bit mounted upon the lower end of the stem, and means to connect the stem and bit to bore a hole when the stem is screwed downwardly. 35

2. A post hole digger comprising in combination, a support, having alined socket elements, a gimbal comprising separable half sections and having shanks fitted in said socket elements, a block pivotally mounted between the arms of the gimbal, a threaded stem operative vertically in the block, adjustable handle bars on the stem, and a bit swiveled upon the lower end of the stem, said bit having an upper transverse recess and a lower cylindrical recess 45 formed therein adjacent the stem socket thereof, and pins transversely projecting through the stem in position to engage said recesses. 50

In testimony whereof, I affix my signature, in the presence of two witnesses.

TOM MOORE.
